UNITED STATES PATENT OFFICE.

WILLIAM H. PEADEN, OF MCKINNEY, TEXAS.

WINDOW-SASH GEARING AND LOCK.

1,370,356.

Specification of Letters Patent.

Patented Mar. 1, 1921.

Application filed April 1, 1920. Serial No. 370,423.

To all whom it may concern:

Be it known that I, WILLIAM H. PEADEN, a citizen of the United States, residing at McKinney, in the county of Collin and State 5 of Texas, have invented certain new and useful Improvements in Window-Sash Gearings and Locks, of which the following is a specification, reference being had to the accompanying drawings.

10 This invention relates to an improved window sash gearing and lock and an object is to provide a device of this kind wherein upon movement of one sash, preferably the lower one, the other sash is likewise movable 15 and also wherein one of two members or both of the gear connections between the sashes are capable of manipulation, whereby one or both of the sashes may be locked, either through the adjustment of one of the 20 gear members in connection with a locking device to secure both sashes, or in connection with the locking device and through the medium of the gear connections on the other sides of the sashes, both sashes may 25 be locked and vice versa.

Another object is to provide a gearing and locking mechanism between the upper and lower sashes, which are simple, efficient and practical in construction and may be 30 cheaply made and sold at a reasonable profit.

Still another object is the provision of a device of this kind, which may be applied to a window and sash construction, at the time 35 of the construction of the window, or may be subsequently applied to windows in use without changing the window construction to any great degree. In fact, the application of the present invention to a window 40 and the sashes therein subsequently to the construction would merely involve the offsetting of racks, and interposing a revolvable shaft in bearings of the frame and between the sashes, in conjunction with adjusting 45 gearing on the shaft for meshing with the racks whereby both of the sashes may be moved in unison for ventilating purposes and either one locked independently or together.

50 A further object resides in the provision of a device of this character whereby the sashes can be adjusted for ventilation at the top of the window or at the bottom, or at the top and bottom, and when adjusted for such 55 ventilation, either one or both of the sashes may be locked.

A still further object embodies a device of this kind which, when the sashes are locked they are practically burglar proof, as the lever which operates the locking means may 60 be so disposed that it cannot be reached by an instrument inserted under the lower sash or over the upper sash.

While the design and construction at present illustrated and set forth is deemed preferable, it is obvious that as a result of a reduction of the invention to a more practical form for commercial purposes, the invention may be susceptible to changes, and the right to these changes is claimed, provided 65 they are comprehended within the scope of what is claimed.

The invention comprises further features and combination of parts, as will be herein-after set forth, shown in the drawings and 70 claimed.

In the drawings:—

Figure 1 is a perspective view of the upper and lower sashes of a window and the locking element interposed and the means 80 for shifting the same.

Fig. 2 is a sectional view through a portion of the window frame and showing the upper and lower sashes and the gear connections between the two, whereby upon movement of one, the other likewise moves.

Fig. 3 is a detail face view of a portion of a frame showing the pinion in engagement with its locking tooth.

Fig. 4 is a transverse sectional view 90 through the window frame and showing the upper and lower sashes and illustrating the gear connections between the two sashes, whereby the two sashes may move when power is applied to one.

Fig. 5 is a transverse sectional view through the window frame, showing the upper and lower sashes, and illustrating the upper and lower sashes locked by the shifting of one of the gears.

Fig. 6. is a transverse sectional view through a portion of a window frame showing the upper and lower sashes locked by both gears being shifted in engagement with their respective locking teeth; and

Fig. 7. is a transverse sectional view through the frame showing the upper and lower sashes locked through one of the gears opposite to that shown in Fig. 5.

Referring to the drawings, 1 designates 110 the window frame which may be of the usual construction, and 2 and 3 denote the upper

and lower sashes, which are mounted in the usual guides 4 of the frame.

Secured to the adjacent faces of the side rails of the upper and lower sashes are rack bars 5 and 6, there being two adjacent each side of the window and one carried by the upper sash and the other by the lower sash. The rack bar 5 on the upper sash is adjacent the extreme edge of the side rail of the sash, 10 while the corresponding bar on the other side of the upper sash is set in from the extreme side edge of the side rail. It will be noted that the rack bar 6 of the lower sash on the inner face of the right hand side rail 15 is set in from the extreme side edge of the side rail, whereas the corresponding rack bar on the other side of the lower sash is adjacent the extreme side edge of the left hand side rail of the lower sash. By this arrangement 20 it will be noted that the rack bars of one pair are offset in one direction, while the rack bars of the other pair on the other side of the sashes are offset in a different direction.

25 Mounted in bearings 7 of the window frame is an operating revoluble shaft 8 and mounted upon the shaft adjacent the opposite sides of the sashes are sliding pinions or gears 9 and 10. Each pinion is elongated so as to engage one or both of its offset rack bars so that the sashes may be adjusted and locked. For instance, the pinion or gear 9 is capable of meshing with both rack bars and in such an instance the 30 two sashes are movable by operating one of them. The same thing is true in regard to the pinion or gear 10 when in engagement with its offset rack bars. The inner faces of the stiles or opposite sides of the window 35 frame are provided with lugs or teeth 11 and 12. Each pinion or gear is sufficiently elongated so as to protrude through the side or stile of the window frame, and is provided with an annular groove 13. Operating levers 14 and 15 are pivotally mounted as at 16 to the stiles of the window frame and are provided with forks 17 for engagement with the grooved ends 13 of the elongated gears or pinions whereby upon 40 movement of the levers, one in one direction, and one in the other direction, and vice versa, the pinions or gears may be adjusted, either in engagement with both sets of rack bars or in engagement with either 45 one of the rack bars of the sets thereof, so that either one or both of the sashes are adjustable, and so that either one or both of the sashes may be locked.

It will be noted that the lugs or teeth 12 50 and 11 are so locked as to be engaged by the teeth of the pinions so as to lock the pinions against rotation, thereby either permitting the sashes to have free movement or permitting the sashes to be locked. The levers 55 14 and 15 are provided with hand grip op-

erated dogs 18 to engage the segment racks 19 in order to hold the levers in different adjusted positions.

Referring to the right hand side of the window it will be noted that by the adjustment of the pinion or gear 9, it may be engaged with both of the rack bars 5 and 6 and should the other pinion 10 be likewise engaged with its respective rack bars the two sashes are capable of movement by the operation of one of the sashes. However, should the pinion 9 be moved so as to engage the rack bar 5 and at the same time engage the lug or locking tooth 11, the upper sash is held against movement and it 70 will be noted that in this instance if the other pinion or gear 10 remains in mesh with both of its respective rack bars without engagement with its respective locking tooth, the lower sash may be moved independently. However, should the pinion or gear 10 be shifted so as to engage its respective rack 6 of the lower sash and in turn engage the locking tooth, and if the pinion 9 still remains in engagement with its rack 90 5 and its locking tooth, the two sashes are locked. It will be noted that before moving the pinion or gear 10 so as to engage its respective locking tooth, the lower sash may be opened a short distance and then the gear or pinion 10 shifted to engage its locking tooth, and in this case the upper sash will be held in a closed locked position, while the lower sash may be held in an open locked position, thereby permitting ventilation at 95 the bottom of the window. This same result can be attained in regard to the manipulation of the gear 10 on the opposite side of the window, and the upper sash locked in an open position and the lower sash 100 locked in a closed position. This is accomplished by shifting the gear 10 so as to engage its locking tooth and remain in engagement with the rack bar 6 of the lower sash and then before moving the pinion or gear 9 to engage its locking tooth, the upper sash may be adjusted to an open position 105 after which the gear or pinion 9 may be shifted to operate into engagement with its tooth, hence locking the upper sash in an 110 open position, thereby permitting ventilation at the top of the window. It will also be noted that the gears or pinions 9 and 10 can be so adjusted and locked that both sashes can be locked in open positions 115 whereby ventilation at the top and bottom 120 of the window may be attained.

It is to be understood that a device of this kind may be applied to all constructions of windows and particularly windows 125 of housed-in sleeping porches and the like, and also in connection with windows of sanatoriums and like places. Furthermore, by the provision of a device of this kind, either one or both of the sashes may be 130

opened a very small degree so that the ventilation of the room may be easily controlled.

Also it is to be remembered that the position of the rack bars may be reversed to that shown, and made of any proportion, and furthermore the pinions or gears may be of any diameter or length and also the locking tooth for each pinion may be modified as found convenient during the course of construction of the window as well as during the application of the device. Moreover, any other suitable means may be employed for shifting the gears or pinions. In other words it is not the aim to confine the invention to the particular form of lever. In fact other means instead of the lever may be employed for shifting the gears.

As illustrated in Fig. 1 it will be noted that the side stiles of the window frame are provided with movable holding strips 22, which are pivotally mounted upon screws, so that by detaching the upper ends of the strips by removing the retaining screws 24 the strips 25 may be swung outwardly to permit one of the sashes, preferably the lower one to be swung outwardly and the rack bars of the lower sash to disengage from the pinions. In this case, the other sash is capable of movement independently. This same principle may be employed with the other face if so desired, it being the aim to limit the use of this principle to one sash only. These movable holding strips 35 may be disconnected from the window frame entirely in order to permit the window sash to be removed. This same principle may be also supplied to the parting strip between the sashes. In other words, the parting strip can be removed so that both sashes may be removed from the window frame, as the parting strips 26 are detachably secured at 27 to the window frame.

The invention having been set forth, what is claimed as new and useful is:—

1. In a combined gear and lock mechanism for window sashes, the combination with a window frame, of upper and lower sashes movable in guides thereof, a revolvable member in bearings of the window frame and interposed between the sashes and provided with operative connections with the window sashes, whereby upon movement of either one of the sashes, the other sash may correspondingly move, said operative connections including a shifting device on the member, and means to be engaged by the shifting member to lock the same in engagement with one or both of the sashes.

2. A combined gear and lock mechanism for window sashes, a frame, upper and lower sashes mounted in guides thereof, a pair of shifting elements, one adjacent each side of the sashes and respectively having operative gear connections with the sashes,

said operative connections including racks relatively offset whereby the shifting of the elements with one or both of the rack bars of each set and in engagement with a locking device, one or both of the sashes may be locked, and a locking device for each of the elements.

3. In a combined gear and lock mechanism for window sashes, a frame, upper and lower sashes mounted in guides thereof, a pair of shifting elements, one adjacent each side of the sashes and respectively having operative gear connections with the sashes, said operative connections including racks relatively offset whereby the shifting of the elements with one or both of the rack bars of each set and in engagement with a locking device, one or both of the sashes may be locked, a locking device for each of the elements, and means for shifting the elements.

4. In a combined gear and lock mechanism for window sashes, a frame, upper and lower sashes mounted in guides thereof, a pair of shifting elements, one adjacent each side of the sashes and respectively having operative gear connections with the sashes, said operative connections including racks relatively offset whereby the shifting of the elements with one or both of the rack bars of each set and in engagement with a locking device, one or both of the sashes may be locked, a locking device for each of the elements, means for shifting the elements, and means for latching the shifting means.

5. In a gear and lock mechanism for window sashes, a window frame, upper and lower sashes operable in guides thereof, the adjacent faces of the side rails of the sashes having rack bars in pairs, the rack bars of each pair being relatively offset, a supporting device in bearings of the frame, shifting elements on the supporting device to be shifted in gear with the rack bars of one or both of the sets, a locking tooth for each of the elements, whereby either one or both of the sashes may be locked in different adjusted positions, and means having operative connections respectively with the shifting elements for moving them.

6. In a device as set forth, a window frame, upper and lower sashes mounted in guides thereof for relative movement, operative gear connections between the sashes, said connections including a supporting shaft positioned in a plane transversely of and between the sashes and parallel with the window frame, slidably shifting pinions independently and revolvably mounted on said shaft, means for locking the pinions, and manual means for shifting the pinions.

7. In a device as set forth, a window frame, of upper and lower sashes operable in guides thereof, operative connections between the sashes, the side stiles of the window frame having pivoted strips, capable of

being swung inwardly whereby one of the sashes may be removed and the operative connections between the sashes severed, and means for detachably connecting certain of the ends of the strips to the window frame.

8. In a combined gear and lock mechanism for window sashes, a window frame, upper and lower sashes mounted therein, a supporting shaft arranged transversely of

10 the window frame and being disposed between the parallel edge faces of the sashes, bearings beyond the opposite side edges of the frame and in which the supporting shaft is mounted, the adjacent faces of the side

15 rims of the sashes having rack bars arranged in pairs, the rack bars of one pair being relatively offset laterally, the rack bars of the other pair being relatively offset

laterally reversely to the rack bars of the first pair, pinions axially slidable on the 20 supporting shaft, one to coöperate with the rack bars of each pair, said pinions having extensions, the side walls of the window frame having openings through which the pinions are operable, means in said openings to be engaged by the pinions for locking the pinions and therefore locking the shafts, and means pivoted on the sides of the window frame and being operatively connected to the extensions of the pinions for 25 shifting them, whereby either one or both of the sashes may be unlocked or locked.

In testimony whereof I hereunto affix my signature.

WILLIAM H. PEADEN.
